UNITED STATES PATENT OFFICE.

JAMES C. NICHOLS, OF BERWYN, AND ELMER RYDER, OF ARGO, ILLINOIS.

CLAMPING DEVICE

1,391,401

Specification of Letters Patent. Patented Sept. 20, 1921.

Application filed September 3, 1920. Serial No. 407,956.

To all whom it may concern:

Be it known that we, JAMES C. NICHOLS and ELMER RYDER, citizens of the United States, residing, respectively, at Berwyn and 5 Argo, in the county of Cook and State of Illinois, have invented new and useful Improvements in Clamping Devices, of which the following is a specification.

This invention relates to a clamp for 10 clamping one end of a shock-absorber strap to the axle of a motor vehicle.

Among the objects of our invention is to provide an improved form of clamp for the purpose mentioned and one that will effectively serve the purpose for which it is designed and be simple in its construction and action and be inexpensive and easy to manufacture and apply to an axle.

Another object of our invention is to provide a form of clamp which will engage the strap without having any of the parts of the clamp extending through the strap and thus avoid weakening the strap by cutting holes in it.

25 A further object of our invention is to provide a form of clamp which will engage the strap in such a manner that the strap may be adjusted to take up or provide slack in the same whenever desired, the clamp being merely loosened for that purpose and without being removed from the axle.

Other and further objects of our invention will appear from the following specification, taken in connection with the accompanying drawings, in which—

Figure 1 is a side view of a shock-absorber such as shown in our prior Patent No. 1,334,390 granted March 23, 1920, and showing the lower end of the strap clamped to 40 the vehicle axle by a clamp of our present invention;

Fig. 2 is an end view of the parts shown in Fig. 1;

Fig. 3 is an enlarged vertical sectional view taken through the axle and clamp on line 3—3 of Fig. 2; and

Figs. 4 and 5 are perspective views of the inner and outer plates of the clamp.

In the drawings, 1 indicates one of the 50 side members of the frame or chassis of an automobile, and 2 one of the axles therebelow, such parts being yieldably connected by a vehicle spring as common in automobile construction.

55 The form of shock-absorber shown is like that disclosed in our said prior patent, and

includes in its construction a flat strap 3 of canvas belting or other desired material and looped at its upper end over a stationary drum 4 secured to the frame member 1 above the axle. The upper end of the strap, as shown, is connected with a spring 5 and the lower end extends to the axle 2 and is secured thereto by a clamp of our present invention.

As shown, the clamp comprises two plates 6, 7 having substantially the same length, but being longer than the width of the strap 3 so that the latter may be clamped between said plates. The plate 6 is the inside one and is made channel shape to fit over one of the outer edges of the base web 8 of the axle 2. This shape of axle is usually found at the front of a car. The outside plate 7 is angle shaped so that it may be applied against the strap and have its lower flange 9 extend under the inner plate and direct the free end of the strap under the axle and gain proper clamping on the strap.

The plates 6, 7 each have two bolt holes 10, 10 and 11, 11, respectively, in their upright webs, and the holes are positioned so that they are on opposite sides of the strap. These holes register when the plates are placed in clamping positions on the axle with the strap between them and enable two 85 clamp bolts 12, 12 to be inserted through the same. Each bolt 12 has a hooked end 13 to engage over that edge of the base web 8 opposite the plates, and a clamp nut 14 is applied on the thread end of the bolt on the 90 outside of the outer plate 7, as shown. The bolts 12, 12 are on opposite sides of the strap and below the base web 8 and do not extend through the strap. This enables the strap to be clamped to the axle without piercing 95 the strap and thus the latter is not weakened by having bolt holes cut in it.

By having the strap extend between the plates 6, 7 and the bolts on the outside sides of the strap, the extreme lower end of the 100 strap, as indicated by 15, may be free and thus permit it being grasped and pulled to take up any slack likely to be produced in the strap by stretching when in use, the nuts 14 being first loosened to permit this being done. Or, should the strap work tighter than required, suitable slack may be given it by loosening the nuts and pulling outward on the portion of the strap above the clamp. The latter is prevented from dropping off of the axle when so loosened by the hooks 13 and the inner plate 6 still retain-

ing their engagement with the axle. This provides for an adjustment of the strap without taking off the clamp, and enables the strap to be easily and readily re-clamped after adjustment has been made. The bolts 12 are made long enough to enable the clamp to be applied to axles or members of various widths, thus permitting the application of the clamp to different makes of motor cars.

10. While we have shown and described herein in our improved clamp used with a shock-absorber of the kind disclosed in our said prior patent, it is to be of course understood that our clamp may be readily used with 15 straps or shock-absorbers of other types, and we do not wish to be limited to the particular kind of shock-absorber shown. Moreover, the details of construction and arrangement of parts of our clamp as shown 20 and described may be variously changed and modified without departing from the spirit and scope of our invention.

We claim as our invention:

1. The combination with a strap and a 25 member, of means for clamping the strap to said member, comprising inner and outer plates adapted to receive the strap between

them, the inner plate having a flange to engage over said member, and clamp bolts extending through said plates on opposite sides of the strap and having hooked ends to engage over that edge of the member opposite to said plates.

2. The combination with a strap and a member, of means for clamping the strap to 35 said member, comprising inner and outer separable plates adapted to receive the strap between them, the inner plate being channel shaped to engage over the adjacent edge of said member, the outer plate being angular 40 and applied against the strap with one of its flanges extending beneath the inner plate, said plates have registering bolt holes on opposite sides of the strap, and clamp bolts inserted through said holes and extending 45 beneath said member and having hooked ends to engage over the other edge of said member.

In testimony that we claim the foregoing as our invention, we affix our signatures 50 this 27 day of August, A. D. 1920.

JAMES C. NICHOLS.
ELMER RYDER.
